UNITED STATES PATENT OFFICE.

CHARLES F. COX, OF BRIDGETON, NEW JERSEY, ASSIGNOR, BY MESNE ASSIGNMENTS,
TO LANDIS MACHINE COMPANY, OF WAYNESBORO, PENNSYLVANIA, A CORPORA-
TION OF PENNSYLVANIA.

THREADING DIE.

Application filed May 11, 1925, Serial No. 29,437. Renewed April 22, 1926.

This invention relates particularly to threading dies having tangentially arranged chasers and the construction is in some respects similar to that shown in the application of Warren E. Glaspey and Frederick W. Cox for pipe threading dies, Ser. No. 598,575, filed Nov. 2, 1922, and in the application of Frederick W. Cox and myself for pipe threading dies, Ser. No. 656,486, filed

10 August 9, 1923.

The principal object of the present invention is to provide in a threading die of the kind referred to an improved construction for the chaser and for the chaser holding 15 clamp whereby the chaser is more firmly held against its seat and is more firmly held against longitudinal movement under the reaction of the cut.

In the accompanying drawing I have 20 shown the embodiment of the invention which I now deem preferable, but it will be understood that the drawing is for illustrative purposes only and that changes may be made within the scope of the claims without 25 departing from the spirit of the invention.

Of the drawings:

Fig. 1 is a plan view of the chaser and chaser holder, the clamp being removed.

Fig. 2 is a plan view of the clamp.

30 Fig. 3 is a rear view of the chaser and chaser holder, the clamp being removed.

Fig. 4 is a rear view of the clamp.

Fig. 5 is a perspective view of the chaser.

35 Fig. 6 is an end view showing the position of the clamp when the chaser is in its rearmost position. This is the condition which prevails with a new chaser.

Fig. 7 is a view similar to Fig. 6 but 40 showing the chaser in a relatively extended position. This is the condition which prevails when the chaser has been reduced in length by repeated sharpenings.

Referring to the drawings, 1 represents a chaser of the tangential type having longitudinal thread cutting teeth 2 on the face thereof. The chaser is also provided with a longitudinal bearing surface 3 which is 45 preferably located along one edge and which is beveled or inclined with respect to the front face and also with respect to the back surface 4. Located in opposed relation to the beveled surface 3 is a clamping surface 5

which also extends longitudinally of the chaser. This clamping surface is immediately adjacent the back surface 4 and is preferably in a plane separated from the corresponding edge of the chaser. The chaser is also provided with a longitudinal groove 6 which is immediately adjacent the clamping surface 5 and which is provided with a wall 60 7 immediately adjacent and at an angle to the said clamping surface 5.

The chaser holder is represented at 8 and this can be of any usual or preferred type. Ordinarily this chaser holder will be so constructed that it can be movably mounted in a suitable die body and moved inward or outward to adjust the die for different diameters of work. The chaser holder 8 is provided with a bearing surface 9 which is 65 adapted to engage the beveled surface 3 of the chaser and is also provided with a bearing surface 10 which is adapted to engage the back surface 4 of the chaser. The body 8 is further provided with a longitudinally 70 extending transversely inclined surface 11 which is located above the main part of the body and adjacent the clamping surface 5 and the groove 6 of the chaser.

The clamp for holding the chaser in place 75 on the body is shown at 12. This clamp is provided with holes 13 adapted to receive bolts 14. These bolts are threaded into the body and serve to connect the clamp with the body and to draw the clamp downward 80 into clamping engagement with the chaser. The clamp has a clamping surface 15 adapted to engage the surface 5 of the chaser and it also has a hook portion 16 which is adapted to enter the groove 6 and engage the wall 90 7 thereof. The clamp is further provided with a heel portion 17 which preferably has an inclined surface 18 adapted to engage with the beveled surface 11 on the body. It will be seen that when the clamp is drawn 95 downward by means of the bolts 14, it will serve to force the chaser downward and backward against the bearing surfaces 9 and 10 of the body.

The clamping surface 5 of the chaser and the beveled bearing surface 3 thereof, instead of being parallel converge toward the rear end of the chaser, that is, they converge from the front cutting end of the

chaser to the opposite end thereof. Ordinarily and preferably the beveled surface 3 is parallel to the cutting teeth 2 and the clamping surface 5 is inclined with respect to the cutting teeth. The clamping surface 15 of the clamp is inclined to conform to the inclination of the bearing surface 5 and the beveled surface 11 of the holder is also inclined longitudinally downward to conform to the said inclination. As the result of the 10 inclination of the before-mentioned surfaces, the clamp is enabled to hold the chaser more securely than it otherwise could. It will be obvious that any rearward longitudinal movement of the chaser could occur only by actually raising the clamp up bodily against the tension of the bolts 14.

In addition to the inclination of the clamping surface as described, I also prefer 20 to transversely incline the groove 6 so that the wall 7 thereof converges rearwardly towards the back surface of the chaser from the front end thereof to the rear end thereof. The hook portion 16 of the clamp is 25 similarly inclined and the beveled surface 11 of the holder is also inclined transversely to conform to the inclination of the wall 7. As the result of this construction it will be apparent that the clamp is still further 30 aided in holding the chaser against rearward longitudinal movement. It will be obvious that even if the surfaces 5 and 15 were not inclined, any rearward movement of the chaser could occur only by forcing 35 the clamp toward the right as viewed in Figs. 6 and 7 and forcing it up the beveled surface 11. Obviously no such movement of the clamp could occur without actually breaking or elongating the bolts 14.

40 With the inclination of both the clamping surface 5 and the groove wall 7, a combined action is attained which makes it practically impossible for any rearward movement of the chaser to occur. This combined action will be more clearly understood 45 from a study of Figs. 6 and 7. Fig. 7 shows the chaser relatively projected, this being the position which the chaser will take after repeated sharpening. It will be clear that any rearward movement of the chaser with 50 respect to the holder and the clamp could occur only by forcing the clamp upward and laterally to a position approximating that shown in Fig. 6. With my improved construction therefore, I make use not only of 55 the frictional engagement between the several surfaces, but I make it mechanically impossible for the chaser to move without actually moving the clamp away from the 60 holder.

In order to further assist in preventing any rearward movement of the chaser, the clamping surface 5 is preferably serrated or knurled in a transverse direction. The 65 chaser is necessarily hard and these serra-

tions will either bite into the surface of the clamp or will mesh with similar serrations which may be formed on the surface of the clamp.

What I claim is:

1. A chasing tool provided with longitudinal thread cutting teeth on one face thereof and having integral opposed longitudinal clamping surfaces which converge from the cutting end of the chaser toward the 75 opposite end.

2. A chasing tool provided with longitudinal thread cutting teeth on one face thereof and having integral opposed longitudinal clamping surfaces one of which extends 80 parallel with the cutting teeth while the other is inclined and converges rearwardly toward the opposed clamping surface.

3. A chasing tool provided with longitudinal thread cutting teeth on the front face 85 thereof and having longitudinal opposed clamping surfaces, said tool including also a longitudinal wall adjacent and at an angle to one of said clamping surfaces, which wall converges with the back surface of the tool 90 and from the cutting end of the chaser toward the opposite end.

4. A chasing tool provided with longitudinal thread cutting teeth on the front face 95 thereof and having opposed longitudinal clamping surfaces, said tool comprising also a longitudinal groove with a wall adjacent and at an angle to one of said clamping surfaces and converging with the back face of 100 said tool from the cutting end thereof toward the opposite end.

5. The combination of a chaser provided with longitudinal thread cutting teeth on one face thereof, and having integral opposed longitudinal surfaces converging from 105 the cutting end of the chaser toward the opposite end, and a holder for said chaser including converging surfaces adapted for close engagement with the said converging surfaces of the chaser.

6. The combination of a chaser provided with longitudinal thread cutting teeth on one face thereof and having opposed longitudinal clamping surfaces which converge from the cutting end of the chaser toward 115 the opposite end, and a chaser holder having relatively adjustable parts constituting a clamp adapted to grip the chaser by engaging said opposed clamping surfaces.

7. In a threading die, the combination of 120 a chaser provided with longitudinal thread cutting teeth on one face thereof and having a longitudinal beveled bearing surface and an opposed longitudinal clamping surface, the said bearing surface extending parallelly with the cutting teeth and the clamping surface being inclined and converging rearwardly toward the bearing surface, a chaser holder having a beveled seat engaging 125 the beveled bearing surface of the chaser, 130

and a clamp connected to the holder and having a clamping surface which engages the clamping surface of the chaser and is similarly inclined.

5 8. In a threading die, the combination of a chaser provided with longitudinal thread cutting teeth on one face thereof and having a longitudinal beveled bearing surface and an opposed longitudinal clamping surface and an opposed longitudinal clamping surface 70 10 face and also having a wall adjacent and at an angle to the clamping surface, the said bearing surface extending parallelly with the cutting teeth and the said wall being inclined and converging rearwardly toward the back of the chaser; a chaser holder having a beveled seat engaging the beveled bearing surface of the chaser, and a clamp having a clamping surface which engages the clamping surface of the chaser and also 75 15 having a hook portion which engages the aforesaid inclined wall and is similarly inclined.

9. In a threading die, the combination of a chaser provided with longitudinal thread cutting teeth on one face thereof and having a longitudinal beveled bearing surface and an opposed longitudinal clamping surface and also having a longitudinal groove with a wall adjacent and at an angle to the clamping 80 20 surface, the said bearing surface extending parallelly with the cutting teeth and the said wall of the groove being inclined and converging rearwardly toward the back of the chaser, a chaser holder having a beveled seat engaging the beveled bearing surface of the chaser, and a clamp connected to the holder and having a clamping surface which engages the clamping surface of the chaser and also having a hook portion which enters the groove in the chaser and engages the aforesaid inclined wall and is similarly 85 25 30 35 40 45 50 55 60 65 70 75 80 85 90 95 100 105 110 115 120 125 130 inclined.

10. In a threading die, the combination of a chaser provided with longitudinal thread cutting teeth on one face thereof and having a longitudinal beveled bearing surface and an opposed longitudinal clamping surface and also having a longitudinal wall adjacent and at an angle to the clamping surface, the said bearing surface extending parallelly with the cutting teeth and the clamping surface being inclined and converging rearwardly toward the bearing surface and the said wall being inclined and converging rearwardly toward the back of the chaser, a chaser holder having a beveled seat engaging the beveled bearing surface of the chaser, and a clamp having a clamping surface which engages the clamping surface of the chaser and is similarly inclined and also having a hook portion which engages the aforesaid inclined wall and is similarly inclined.

11. In a threading die, the combination of a chaser provided with longitudinal thread

cutting teeth on one face thereof and having a longitudinal beveled bearing surface and an opposed longitudinal clamping surface, the said bearing surface extending parallelly with the cutting teeth and the clamping surface being inclined and converging rearwardly toward the bearing surface, a chaser holder provided with bearing surfaces respectively engaging the beveled bearing surface and the back of the chaser, the said holder also being provided with a transversely beveled surface which is also longitudinally inclined to conform to the inclination of the clamping surface on the chaser, and a clamp connected to the holder and having surfaces which respectively engage the inclined clamping surface of the chaser and the similarly inclined beveled surface of the holder.

12. In a threading die, the combination of a chaser provided with longitudinal thread cutting teeth on one face thereof and having a longitudinal beveled surface and an opposed longitudinal clamping surface and also having a longitudinal groove with a wall adjacent and at an angle to the clamping surface, the said bearing surface extending parallelly with the cutting teeth and the said wall of the groove being inclined and converging rearwardly toward the back of the chaser, a chaser holder provided with bearing surfaces respectively engaging the beveled bearing surface and the back of the chaser, the said holder also being provided with a transversely beveled surface which is also longitudinally inclined to conform to the inclination of the said wall of the groove, and a clamp connected to the holder and having surfaces which respectively engage the clamping surface of the chaser and the longitudinally inclined beveled surface of the holder, the said clamp also having a hook portion which enters the groove in the chaser and engages the aforesaid inclined wall and is similarly inclined.

13. In a threading die, the combination of a chaser provided with longitudinal thread cutting teeth on one face thereof and having a longitudinal beveled bearing surface and an opposed longitudinal clamping surface and also having a longitudinal groove with a wall adjacent and at an angle to the clamping surface, the said bearing surface extending parallelly with the thread grooves and the clamping surface being inclined and converging rearwardly toward the bearing surface, and the said wall of the groove being inclined and converging rearwardly toward the back of the chaser, a chaser holder provided with bearing surfaces respectively engaging the beveled bearing surface and the back of the chaser, the said holder also being provided with a transversely beveled surface which is also longitudinally inclined to conform to the

- inclination of the said clamping surface on the chaser and the inclination of the said wall of the groove, and a clamp connected to the holder and having surfaces which respectively engage the inclined clamping surfaces of the chaser and the longitudinally inclined beveled surface of the holder, the said clamp also having a hook portion which enters the groove in the chaser and engages the aforesaid inclined wall and is similarly inclined.
14. In a threading die, the combination of a chaser provided with longitudinal thread cutting teeth on one face thereof and having a longitudinal beveled bearing surface and an opposed longitudinal clamping surface with transverse serrations therein, the said surfaces converging from the cutting end of the chaser to the opposite end, a chaser holder having a beveled seat engaging the beveled bearing surface of the chaser, and a clamp connected to the holder and having a clamping surface which engages the clamping surface of the chaser.
15. For a threading die, a chaser provided with longitudinal thread cutting teeth on one face thereof and having a longitudinal beveled bearing surface and an opposed longitudinal clamping surface which converge from the cutting end of the chaser to the opposite end.
16. For a threading die, a chaser provided with longitudinal thread cutting teeth on one face thereof and having a longitudinal beveled bearing surface and an opposed longitudinal clamping surface, the said bearing surface extending parallelly with the thread
- grooves and the clamping surface being inclined and converging rearwardly toward the bearing surface.
17. For a threading die, a chaser provided with longitudinal thread cutting teeth on one face thereof and having a longitudinal beveled bearing surface and an opposed longitudinal clamping surface and also having a longitudinal groove with a wall adjacent and at an angle to the clamping surface, the said bearing surface extending parallelly with the thread grooves and the said wall of the groove being inclined and converging rearwardly toward the back of the chaser.
18. For a threading die, a chaser provided with longitudinal thread cutting teeth on one face thereof and having a longitudinal beveled bearing surface and an opposed longitudinal clamping surface and also having a longitudinal groove with a wall adjacent and at an angle to the clamping surface, the said bearing surface extending parallelly with the thread grooves and the clamping surfaces being inclined and converging rearwardly toward the bearing surface, and the said wall of the groove being inclined and converging rearwardly toward the back of the chaser.
19. For a threading die, a chaser provided with longitudinal thread cutting teeth on one face thereof and having a longitudinal beveled bearing surface and an opposed longitudinal clamping surface with transverse serrations therein, the said surfaces converging from the cutting end of the chaser to the opposite end.

CHARLES F. COX.
